UNITED STATES PATENT OFFICE.

CARL F. EFRAMSON, OF MINNEAPOLIS, MINNESOTA.

HEATER CONSTRUCTION.

Application filed September 19, 1927. Serial No. 220,532.

This invention relates to heating systems and the primary object is to provide means of a novel, efficient and practical nature, and as an attachment for stoves and furnaces, for increasing the heating efficiency thereof, and for preventing the escape of hot air and gases up the chimney of the building. More particularly the object is to provide an improved form of radiator and means for selectively cutting it into or out of the draft circuit of a heating unit, whereby the normal line of draft need not be interfered with when a fire is being started, but wherein the radiator may be cut into the draft line, when the fire is well under way, so as to cause the draft to pursue a longer course and thereby exhausting all the heat before it reaches the chimney proper. Further and more specific objects will be disclosed in the course of the following specification, reference being had to the accompanying drawings, wherein:

Fig. 1 is a side elevation of a hot air heating furnace unit in which my invention is incorporated and is shown by dotted lines.

Fig. 2 is a rear view of the construction shown in Fig. 1 but with various parts broken away for purpose of illustration.

Fig. 3 is a side view of the device as shown in Fig. 1, but with the greater portion thereof cut away on a vertical section taken diametrically from front to rear.

Fig. 4 is a plan view in section as seen substantially on the irregular line 4—4 in Fig. 3.

Referring to the drawings more particularly and by reference characters, 7 designates the usual base of a hot air furnace having a combustion chamber 8, a fire pot 9, a fire door 10, an ash pit door 11, and an outer shell 12 having one or more cold air inlet pipes 13, and suitable warm air discharge pipe connections 14 in the canopy or top 15 which is spaced above the stove unit or heater proper. These parts are all of common and well known construction, except that I prefer to make the combustion chamber 8 out of sheet metal rather than cast iron so that it will more readily conduct heat. This will of course render it more susceptible to destruction by the heat of the fire, but I find that this disadvantage is more than counterbalanced by the noted advantage, and I have provided the shell 12 with suitable doors 12^a, so as to render it convenient to replace or repair the shell 8 when necessary. The top of the chamber 8 consists of an inverted cone 16, which extends well down into the chamber and by

reason of its shape of course offers a far greater heating area than a flat or slightly rounded top would do. In order that the tip of the cone will not readily burn out, I provide it with a shield 17, releasably held in place by a spring arm 18, fastened as at 19. When one shield burns out it can readily be replaced through the fire door 10.

The air circulating through the pipes (not shown) of the system and through the rooms of the house comes in through the opening 13, and while passing up between the shells or housings 8 and 12 becomes heated in the usual manner before escaping through the outlets 70 14 and passing to the rooms.

The chamber 8 is connected with a flue pipe 21, (leading to the chimney) by a housing 22, through which the draft is controlled and deflected by a damper 23, which is pivoted as at 75 24, and is operated by suitable means such as a rod 25 having a handle at its outer end. When this rod is pushed in the damper is swung into the position shown in Fig. 4, thus permitting a direct draft from the fire into the flue 21. This is the condition desired when a fire is being started and it is desired to provide as strong a draft as possible.

When the rod 25 is pulled out, after the fire is well started the front end of the damper 23 is closed against the front end of an angularly disposed partition 26. This shuts off the direct line of draft which is then separated by the V-shaped divider 23, 26, and is deflected into a pair of oppositely disposed, laterally and forwardly directed radiators A and B. These radiators consist, primarily, of upper horizontal tubes or flues 27 which communicate at their rear ends with the housing 22, a pair of forward hollow legs 28, which connect the flues 27 with the forward ends of lower horizontal flues 29, and a rear, vertical flue 30 which connects at its lower end with the flues 29, while its upper end opens into the housing 22 immediately rearward of the deflectors 23 and 26. It will thus be seen that as soon as the direct draft has been cut off, as above noted, the updraft in the chimney will immediately draw the hot gases and air through the flues 27, 28, 29 and 30, before they can pass to the chimney, and by that time most if not all of the heat in such gases has been absorbed by the radiators A and B, and as they thus become heated they will greatly raise the temperature of the air circulating up between the shells 8 and 12. If the draft should become sluggish in mild weather or if

the fire should become low it is a simple matter to temporarily open the damper 23 to effect a direct draft.

As shown in the drawings the height of the radiators A and B is substantially the same as that of the combustion chamber 8 but it is to be understood that it is not necessary to so limit the vertical dimensions of the radiators, and that the present disclosure is merely illustrative.

It is understood that while I have shown my invention as applied to hot air heating plants, it may also be used to advantage in ordinary stove constructions as well as other types of heating units. It is further understood that various modifications may be made in the general design and structural details of the invention as herein described, provided, however, that said modifications come within the spirit and scope of the appended claims.

Having now therefore fully shown and described my invention, what I claim to be new and desire to protect by Letters Patent is:

- 25 1. The combination with a heating unit, of means for utilizing the heat of air and gases thrown off by the fire of the unit, comprising radiator forming flues extending laterally about the heating unit, and means for deflecting such air and gases from a direct line of draft and through said flues, said means comprising a stationary deflector and a movable damper acting deflector co-operating therewith.
- 30 2. The combination with a heating unit, of means for utilizing the heat of air and gases thrown off by the fire of the unit, comprising

radiator forming flues extending laterally about the heating unit, and means for deflecting such air and gases from a direct line 40 of draft and through said flues, said means comprising a stationary deflector and a movable damper acting deflector forming a V-shaped partition therewith.

3. The combination with the combustion 45 chamber and outer housing of a hot air heating plant, of a casing interposed between the chamber and the draft flue through which a direct draft may pass from the chamber to the flue, a pair of laterally disposed radiators arranged between the combustion chamber and said housing and circuitously connected with said casing, and means interposed between the inlet ports of the two radiators and separating the inlet and outlet ports of the respective radiators for selectively deflecting said direct draft to the radiators.

4. The combination with the combustion chamber and outer housing of a hot air heating plant, of a casing interposed between the 60 chamber and the draft flue through which a direct draft may pass from the chamber to the flue, a pair of laterally disposed radiators arranged between the combustion chamber and said housing and circuitously connected 65 with said casing, and means normally separating the inlet and outlet ports of the radiators for selectively deflecting said direct draft to the radiators, said means consisting of a stationary deflector for one of the radiators and an adjustable deflector operatively associated with the inlet of the other radiator.

In testimony whereof I affix my signature.
CARL F. EFRAMSON.
